UNITED STATES PATENT OFFICE.

LUTHER C. CROWELL, OF BROOKLYN, ASSIGNOR TO R. HOE & CO., OF NEW YORK, N. Y.

SHEET-DELIVERY APPARATUS FOR PRINTING-MACHINES.

SPECIFICATION forming part of Letters Patent No. 292,993, dated February 5, 1884.

Application filed June 20, 1881. (No model.)

To all whom it may concern:

Be it known that I, LUTHER C. CROWELL, a citizen of the United States, residing in the city of Brooklyn, county of Kings, and State of New York, have invented certain new and useful Improvements in Sheet-Delivery Apparatus for Printing-Machines, fully described and represented in the following specification and the accompanying drawings forming a part 10 of the same.

The object of my invention is to produce a machine by which a web of paper can be printed, cut into sheets, and the same delivered folded either as single sheets with or without 15 a supplement folded in each, or as two sheets superposed with or without a supplement sheet; and the invention consists of the combinations of parts in such a machine, as will be hereinafter fully described and claimed.

20 In the drawings, Figure 1 represents a side elevation of a machine in which the present inventions are carried out. Fig. 2 is a plan view of the same. Fig. 3 is a vertical longitudinal section of the same on the line x of 25 Fig. 2. Fig. 4 is an end view of the same, the printing mechanisms being omitted. Fig. 5 is an end view of the gathering or collecting cylinder by which sheets are superposed while moving onward.

30 In these drawings, A and B represent the last pair of the well-known web-printing mechanism, the impression-cylinder A and the type-cylinder B being journaled in the frame 9 of the machine. In advance of these cylinders 35 there is a roller, 8, journaled in standards that rise from the frame 9, over which roller the printed web 50 is led. A rotary cutter or slitter, 7, is secured to a shaft that is also journaled in said standards, which cutter is arranged to bear upon the roller 8, while both 40 the roller and shaft are free to revolve in their bearings. A sheet-turner, 46, in this instance constructed substantially as is described in Patent No. 181,250, dated August 22, 1876, 45 depends from a bar, 47, that is secured to the side frames. In advance of these parts there is a cylinder or carrier, C, the shaft of which is journaled in bearings in the frame 9. This cylinder has journaled near its periphery, in a 50 recess, a shaft, 18, carrying four equidistant

folding-blades, 20. One end of this shaft projects beyond the end of the cylinder C, and is provided with four equidistant lever-arms, 68. (See Fig. 5.) A portion of this shaft between the arms 68 and the head of the cylinder C is made 55 square, and upon this squared portion a spring, 66, secured to the end of the cylinder, is arranged to bear and act as a stop for the shaft, to hold it in any position to which it has been turned. Opposite the recess in which the shaft 60 18 is hung is another recess in the cylinder C, in which a shaft, 24, having its bearings in the ends of the cylinder, is journaled. This shaft is provided with two or more pins, 25, for entering and holding the paper, and at or 65 near one end with a crank, 27, to which a connecting-rod, 28, is attached, said connecting-rod in this arrangement passing through an eye in a bearing-block, 51, attached to the end of the cylinder, and it is provided with a collar, 29, between which collar and the said bearing-block 51 a spiral spring, surrounding said connecting-rod, is confined. The outer end of this connecting-rod is rounded and projects 70 slightly beyond the periphery of the cylinder 75 C for a purpose to be explained. Projecting over one edge of the recess, opposite the shaft 18, is a serrated cutting-blade, 26, provided with apertures 21, through which the pins 25 may work. On the opposite side of this recess is a 80 spring-plate, 23, the function of which is to hold the paper while it is being cut against the cutting-blade, (to be described,) that coacts with the cutting-blade 26 in performing the cutting operation. Another cylinder, D, the shaft 30 of 85 which is journaled in the frame 9, carries devices that co-operate with those of the cylinder C. For a purpose that will presently appear this cylinder D is made, as shown, twice the diameter of the cylinder C. At points dia- 90 metrically opposite to each other the periphery of the cylinder D is provided with recesses, in each of which is journaled a rock-shaft, 5, having its bearings in the ends of the cylinder, to which shaft are secured two or more vi- 95 brating nipping-jaws, 33. One end of each of these rock-shafts 5 projects beyond the end of the cylinder D, and is there provided with a crank-arm, 40, having a roller running in contact with a stationary cam, 41, secured to the 100

frame 9. This stationary cam 41 is so shaped as to cause the nipping-jaws 33, through the rock-arm 40, to be moved toward and into nipping contact with the wall or stationary jaw 65, their contrary or opening movement, when released from said cam, being caused by a spring, 100. The cylinder D is also provided with cam-plates 34, placed in such positions that the end of the connecting-rod 28 may roll 10 in contact therewith and be operated to rock the pins 25, and withdraw them from the paper at proper times, as will be hereinafter more fully explained. These cam-plates 34 are made capable of being removed from operative position 15 on the cylinder D, as is illustrated by the absence of one of them in Fig. 1. The cylinder D is further provided upon its periphery with two oppositely-situated cutting-knives, 31 32, the serrated edge of each of which works in 20 connection with the serrated edge of the cutter 26, and with it forms a cutting mechanism that will operate to sever the paper. The cylinders A, B, C, D are all geared together, so that their peripheral surfaces will run at a uniform 25 speed, the usual gear-wheels, 101 102 103, being supplied for that purpose with an intermediate 30 to secure their proper direction of travel.

The mechanisms operate in the following manner: If it be desired to deliver single sheets each with an inset supplement, the endless web 50 will be of a width sufficient to receive impressions of appropriate matter for the main and supplement sheets, and will be split on a line dividing the main and supplement portions by the cutter 7, after it has left the impression and type cylinders, and is passing between the roller 8 and cutter 7, which slits it longitudinally and forms it into two webs. The main portion of the web passes 35 directly to the cylinder C, while the narrow or supplement portion 14 is led from the roller 8 down and around the turner 46, and back up over the roller 8, (see Fig. 4,) it being by this operation transferred laterally, so as to be 40 brought beneath and associated with the main portion of the web, with which it then passes onto the cylinder C. The pins 25 on this cylinder C pass through the leading ends of the associated main and supplement webs, and carry 45 said webs onto the cylinder and around with it, said webs overlying the recess in the cylinder and the folding-blade 20 then slightly protruding therefrom. As the cylinders C, D revolve and the folding-blade recess in C and 50 the jaw-recess in D approach each other, a folding-blade, 20, will be carried into the range of action of a set of jaws, 33, which latter, being operated by the rock-arm 40, will, while said arm is passing over the cam 41, be quickly 55 moved upward and closed, in such movement sweeping within the folding-blade recess in the cylinder C, so as to engage and force the one of the folding-blades 20, then in operative position, outward beyond the periphery of the 60 cylinder C and within the jaw-recess of the cylinder C, whereby the paper is engaged and

pressed on its fold-line and between the jaws 33 and the wall or jaw 65, by which jaws the doubled portion of the paper and the folding-blade within it will be embraced and held as 70 said jaws close. As the cylinders C and D continue to revolve, the folding-blade 20 will be withdrawn, leaving the doubled portion of the paper within the grasp of the jaws, which then completely close to secure it. At or 75 about the moment when the jaws have commenced to act upon the folding-blade, as just described, the cam-plate 34 comes into contact with the rounded end of the connecting-rod 28, and rocks the pins 25 within the periphery of the cylinder C, thus withdrawing 80 them from the leading edge of the paper and releasing it. The paper held by its doubled part in the nip of the jaws, as just described, is carried onto the surface of the cylinder D, 85 and when the folding is completed the jaws are opened to release it. In folding or doubling the paper into the nip of the jaws, as just described, the folding-blade will have been moved about one-eighth of a revolution, and, 90 carrying with it the shaft 18, it will have brought one of the rock-arms 68 into such a position that, as the cylinders C, D revolve, said lever or arm 68 will strike a tappet, 69, that is secured to the frame 9, and be rocked 95 so as to cause the shaft 18 to turn far enough to complete a quarter-revolution, in making which the folding-blade is withdrawn from the doubled part of the paper. At the end of this movement of the shaft 18 the spring 66 bears 100 upon one of its squared sides and suspends and secures the shaft in that position until it is again turned in the operation of folding the paper, the folding-blades then standing within the periphery of the cylinder C, as in Fig. 1, 105 with one in position to be engaged by the folding-jaws in the next folding operation. The paper held by its doubled portion in the jaws of the cylinder D will be carried onward with that cylinder, and when the cylinders 110 have so far revolved as to bring the serrated edge of the plate 23 opposite the serrated edge of the plate 32 (or 31, as may be) said plates will articulate and cause the paper to be severed, during which operation the paper will 115 be held by the flexible plate 23 against the plate 32. Just before this occurs the paper just back of the serrated edge of the cutting-blade 26 is again impaled upon the pins 25, which have been rocked outward by the action of the spring 100, as soon as the cam-plate 34 was carried out of contact with the rod 28. 120

The paper, while held by its doubled edge in the nip or bite of the jaws 33, may be released at any time after the severing has taken 125 place, as above described, by properly shaping the cam 41, against which the rocking arm 40, attached to the shaft carrying said jaws, works.

The operation just described is repeated at 130 each revolution of the cylinder C, both cam-plates 34 being adjusted in working position,

both jaws 33 being in operation, and the cutting-blades 31-32 alternately operating in connection with blade 26, and thus papers are delivered with a supplement folded within them. If desired, further folds may be made in the transversely-folded paper by any of the well-known devices for folding paper.

If it be desired to deliver papers each consisting of two sheets superposed and folded together without a supplement, and with different reading matter upon each of their pages, the first type-cylinder, as well as the last, A, must be increased in size, in order to carry the requisite number of printing plates or forms, as is well known. One of the cam-plates 34 will then be removed, as in Fig. 1, or rendered inoperative in any common way, and one set of jaws, 33, will also be rendered inoperative in any common way, as by removing its arm 40. The web of paper, of a width equal to the length of the folding-blade, or less, as may be desired, passing from the last impression and type cylinders B A over the roll 8 and cylinder or carrier C, is impaled upon the pins 25 of the cylinder C, and carried by such pins as the cylinder revolves until the cutting-blade 26 severs the web. Just before this cutting takes place the web is again impaled upon the pins 25, which are not withdrawn during this revolution on account of the absence of one cam-plate 34, and the cylinder C continuing to revolve, the blades 31 and 26 severing the second sheet. The two sheets thus formed are superposed one on the other upon the cylinder C, which thus becomes a gathering-cylinder, upon which the pins 25 serve to hold the leading edges of the two sheets in perfect register, which register is preserved during the subsequent manipulation of such sheets. On this second revolution of the cylinder C the set of jaws 33-65, that have not been thrown out of operation, coming opposite one of the folding-blades 20, cause it to tuck the fold-line of the sheets between said jaws, as before described, and as soon as the jaws have grasped the doubled portion of the sheets the cam 34, which has not been removed or thrown out of operation, coming in contact with the rounded end of the connecting-rod 28, causes the pins 25 to be withdrawn within the cylinder, thus releasing the leading ends of the sheets. Upon the further revolution of the cylinders C D the second cutting-plate 32, operating in connection with the cutting-plate 26 on the cylinder C, again severs the web, the pins 25 having just previously to this cutting been again projected by the spring, and these pins again have hold of the leading edge of the web. The two sheets, superposed with their double portions held in the nip of the jaws 33-65, are carried around on the cylinder D until the shape of the cam 41 opens the jaws, when the sheets are released and either piled or folded again by any of the common mechanisms for these purposes.

If it be desired to produce papers consisting of

two full sheets superposed and folded together, and also with a supplement within them, the printed web of paper will be of a width sufficient to provide the supplement portion to be split off, as before described; which supplement portion will be turned under the main web by the turner, as before described, and the webs thus associated will be gathered together or superposed on the cylinder C as it revolves, 75 be severed, and delivered folded. This association may also be accomplished by simply leading the supplement web in under the main web after the latter has been severed and turned; but in this case two slitters will have 80 to be used and a web-guide to properly direct the supplement web.

When it is desired to paste the supplement and main sheets constituting the signature together, it may be accomplished by any of the 85 well-known pasting devices.

It is evident that the printed paper may be led over or through a longitudinal folding mechanism like any shown in patents heretofore granted to me, or substantially the same 90 in mode of operation, and then to the cutting and folding devices shown herein; or this longitudinal folding may be applied to once-folded sheets.

The sheet-registering pins may be applied 95 to any form of gathering or collecting mechanism wherein two or more sheets are associated—such, for instance, as are shown in Letters Patent Nos. 192,510, 192,954, 191,494, 197,693, 253,325, or the patent granted to me 100 May 1, 1883.

Although means for associating webs, first laterally and afterward longitudinally, (as by bringing different portions of laterally-associated webs together through a collecting mechanism,) and, in conjunction therewith, means for slitting a wide web longitudinally to produce narrow webs, and cutting devices to sever the webs transversely to produce sheets, and mechanisms for folding said sheets transversely 110 and the sheets or webs longitudinally, are either shown or described herein, the same are not claimed herein, but are made the subject-matter of another application filed June 22, 115 1883.

The following is therefore alone claimed:

1. A cylinder or revolving carrier provided with means for gathering or collecting sheets, and with pins for securing a proper register of the sheets, substantially as described. 120

2. The combination, with a rotating carrier provided with nipping-jaws, of a carrier provided with means for gathering or collecting sheets, and with a folding-blade co-operating with said jaws, all substantially as described. 125

3. The combination, with the pins 25, their shaft, and connecting-rod 28, of a rotating cam, as 34, to cause said pins to recede within the cylinder C, substantially as described. 130

4. The combination, with a revolving carrier, a shaft supported thereby, and carrying a multiplicity of folding-blades and a corresponding

number of lever-arms, and with a companion carrier, provided with nipping-jaws co-operating with said folding-blades, of means for bringing one of said blades into position to co-
act with said jaws at each revolution of the folding-blade carrier, all substantially as described.

In testimony whereof I have hereunto set my hand in the presence of two subscribing witnesses.

LUTHER C. CROWELL.
